UNITED STATES PATENT OFFICE.

WILLIAM F. MEISTER, OF MARIETTA, OHIO, ASSIGNOR TO THE PATTIN BROS. COMPANY, OF MARIETTA, OHIO, A CORPORATION OF OHIO.

VALVE FOR AIR-COMPRESSORS, &c.

1,188,969.

Specification of Letters Patent. Patented June 27, 1916.

Application filed August 11, 1915. Serial No. 44,876.

To all whom it may concern:

Be it known that I, WILLIAM F. MEISTER, a citizen of the United States, and resident of Marietta, in the county of Washington and State of Ohio, have invented certain new and useful Improvements in Valves for Air-Compressors, &c., of which the following is a specification.

The object of this invention is to provide a simple and highly efficient valve for compressors, blowing engines, etc., the valve being constructed of relatively thin flexible metal which provides its own spring action, avoiding the use of separate springs commonly employed. The valve is maintained in proper working condition, notwithstanding very frequent and rapid vibrations to which it is subjected, by exposing its flexing portions to the air which is admitted or discharged through the valve, thereby preserving the temper of the metal and rendering it responsive to as rapid action as may be required.

In the preferred embodiment of the invention the valve is of disk form, with a plurality of laterally separated port-covering portions radiating from a central securing portion, whereby each port-covering portion may flex independently with a total absence of buckling tendency.

In the accompanying drawings, Figure 1 is a longitudinal section of one end of a compressor equipped with the improved valve, the inlet valve being mounted on the compressor cylinder head, and Fig. 2 is an elevation of the cylinder head with the inlet valve attached thereto. Fig. 3 is a view similar to Fig. 1, illustrating the inlet valve mounted in the side of the cylinder. Fig. 4 is a detail view of the improved valve as applied to the compressor outlet.

Referring to the drawings, the compressor cylinder 2 is cored to provide the usual air inlet channel 3 and outlet channel 4. In the adaptation shown in Figs. 1 and 2 cylinder head 5 is cored to form the encircling air channel 6 with which inlet channel 3 is in communication, and with ports 7 connecting channel 6 with the cylinder. The inner face of head 5 comprises a support for the inlet valve.

The valve is formed of a sheet of thin resilient metal, and in the arrangement shown is of disk-like form and has a hollow hub portion 8 adapted to fit around boss *a*

on the inner face of head 5 and secured to the head by screws *b*. The disk-like plate is formed with radial slots 9, forming a series of independently flexible valve segments. Each segment is cut out or apertured at 10, thereby leaving the marginal portions 11 which connect the port-covering outer portion 12 of each segment with supporting portion 8. With the valve formed of resilient sheet metal, portions 11 constitute spring arms for affording the port-covering portions 12 sensitive movement in response to air pressure, the direction of such pressure being determined by the movement of piston 13. As illustrated in Fig. 1, the end face of cylinder 2 is recessed at 14 to receive the valve and to provide a stop for limiting the inward movement of the segments on the filling stroke of the piston as in Fig. 1, and on the return or discharging stroke ports 7 are closed by the port-covering portions 12 under the spring action of arms 11 plus the air pressure.

The discharge valve 15, controlling communication with outlet channel 4, is preferably arranged at the top or at one side of the end of the cylinder and is secured to the removable seat 16 ported at 17 for the passage of air therethrough. The discharge valve, shown in detail in Fig. 4, is of the same construction as the above described inlet valve excepting that its center is solid save for an aperture to pass a securing screw 18, the rim-like peripheral portions 12 being adapted to open and close ports 17, as will be understood. Seat 16 with the valve secured thereto is removably mounted in the angular end of channel 4 which communicates with the cylinder, being inserted through an external opening closed by cap 19 and held in place by screw 20 adjustable through the cap. The cylinder end may be equipped with one or more discharge valves as may be necessary.

In the adaptation shown in Fig. 3, the inlet valve is shown at one side of the cylinder at 21 in the same relative position as the discharge valve, in this arrangement the cylinder head 6' extending well into the cylinder end and recessed at 6'' to afford ample clearance. When thus arranged, inlet valve 21 is of the same construction as the discharge valve and is similarly secured to the ported and seat-forming inward extension 22 of cap 23.

It is characteristic of the valve, both inlet and discharge, that the spring elements for maintaining it normally in port-closing position and for opposing opening movement thereof are embodied in the valve itself, being the radial rim-like portions 11, which readily flex in response to the opening and closing movements. And as these flexing portions are directly in the path of the air flow, inward or outward, controlled by the valve, the cooling effect prevents overheating and preserves their temper.

With the valve divided into segment-like sections by slots 9, each section is of such relatively small area that there is no buckling tendency such as would be present if the valve were a continuous uninterrupted plate. The shape and contour of each port-covering portions 12 is thus preserved, and the port controlled thereby is effectively sealed when the valve is closed.

The improved valve is fully sensitive under the very rapid vibrations to which compressor valves are subjected, the segmental portions opening instantly under the action of the suction strokes of the piston and closing as quickly on the compression strokes. While only a portion of a compressor cylinder is shown, it will be understood that the improved valve may be utilized for either single or double-acting compressors, in the latter type each end of the cylinder having the same valve equipment. It will also be understood that the

invention is well adapted for blowing engines and other machines in which sensitive quick-acting valves are required.

I claim:

1. A valve for compressors, etc., formed of relatively flexible metal and consisting of a central supporting and securing portion, a series of segmental port-covering portions separated from each other for independent flexing and with spring arms integral with the supporting portion and with the port-covering portions, each segment of the valve comprising several of said spring arms and being open for the passage of air between its said port-covering and supporting portions and between said arms.

2. A valve for compressors, etc., formed of a disk of thin flexible spring metal cut to form a series of independently flexible segments and a supporting and securing portion common to and integral with all of said segments, each segment having a port covering portion at its free end and radial rim arms connecting the port covering portion with the supporting and securing portion, each segment being open between said arms and said portions, substantially as described.

In testimony whereof I affix my signature in presence of two witnesses.

WILLIAM F. MEISTER.
